Primary Examiner — Jeffrey D Asch*(74) Attorney, Agent, or Firm* — Roland J. Tong; Brooks Kushman P.C.(57) **CLAIM**

The ornamental design for a smartphone printer, as shown and described.

DESCRIPTION

FIG. 1 is a perspective view of the smartphone printer of the present invention showing a smartphone that can be attached thereto.

FIG. 2 is a left side view of the smartphone printer shown in FIG. 1.

FIG. 3 is a right side view of the smartphone printer shown in FIG. 1.

FIG. 4 is a front view of the smartphone printer shown in FIG. 1.

FIG. 5 is a rear view of the smartphone printer shown in FIG. 1.

FIG. 6 is a top plan view of the smartphone printer shown in FIG. 1; and,

FIG. 7 is a bottom plan view of the smartphone printer shown in FIG. 1.

The broken lines shown in the figures that are immediately adjacent to surfaces that include shading and define unshaded regions, represent the bounds of the claim, while all other broken lines are directed to environment and are for illustrative purposes only; the broken lines form no part of the claimed design. All surfaces that are uninterrupted by a broken or solid line and include surface shading at any point thereon are included in the claim.
